To all whom it may concern:

Be it known that I, James R. Neuendorf, a citizen of the United States, residing at South Bend, in the county of St. Joseph and State of Indiana, have invented a new, original, and ornamental Design for a Child's Play Table, of which the following is a specification, reference being had to the accompanying drawings, forming a part thereof.

Figure 1 is a perspective view of a child's play table showing my new design;

Figure 2 is a top plan view of the table, and

Figure 3 is a side elevational view thereof with a portion of one leg broken away for convenience of illustration.

I claim:

The ornamental design for a child's play table, as shown and described.
